STANLEY A. JACQUES, OF CHICAGO, ILLINOIS, ASSIGNOR TO INTERNATIONAL COMBUSTION ENGINEERING CORPORATION, A CORPORATION OF DELAWARE

APPARATUS FOR BURNING PULVERIZED COAL

Application filed July 30, 1925. Serial No. 46,991.

This invention relates to the art of burning pulverized coal and is particularly useful in the burning of finely divided fuel under stationary boilers.

In many forms of apparatus for the burning of pulverized coal under stationary boilers, the fuel is admitted thru a plurality of burners arranged in a row. The installations are operated at all ratings from purely nominal loads to maximum or peak loads, the amount of coal being burned at any particular time being dependent upon the rating at which the installation is then being operated. To meet this condition it has been customary to cut out one or more burners or to increase the number of burners which are supplying coal as the case may be. No difficulty is encountered when all of the burners are feeding coal. However, it is quite difficult to secure a balanced flame when cutting out one or more burners, the disposition of the burners in present standard practice being such that an unbalanced flame condition arises by virtue of the fact that more coal will be admitted in one part of the combustion chamber than in another or other parts.

The primary object of my invention, therefore, is to provide an arrangement whereby it is possible to more nearly approximate a balanced flame condition at any ratings, from peak loads down.

How the foregoing, together with such other objects as may hereinafter appear, or are incident to my invention, are realized, is illustrated in the accompanying drawings, wherein—

Fig. 1 is a diagrammatic partial front elevation of a boiler and furnace setting equipped with my improvements;

Figs. 2, 3 and 4 inclusive illustrate how the invention may be put into effect with the arrangement shown in Fig. 1;

Fig. 5 shows a modified arrangement for carrying out my invention; and

Fig. 6 shows another modification applicable where direct firing is desired.

Referring now to Fig. 1 the reference character A indicates a combustion chamber which has an outlet towards the rear of the arch or roof 7, thru which the products of combustion pass upwardly to the boiler 8, which may be of any conventional design.

The front wall of the combustion chamber is provided with a plurality of air inlets 9 thru which air may be admitted for combustion, under control.

The coal preferably with carrying air, is conducted from a suitable source of supply to the furnace by means of a pipe or pipes 10, in this case but one pipe being shown. This pipe 10 branches, in the present showing there being three branches 11. Each of the branches is controlled by a damper, or other suitable control device 12.

Secured to each pipe is a burner nozzle 13, these burner nozzles changing from a circular cross section to a flat elongated cross section. The burner nozzles are, therefore, of the fish-tail type. Surrounding the burner nozzles are burner castings 14 thru which additional air for combustion may be admitted.

Referring now to Fig. 1 it will be seen that the middle nozzle 13 is located centrally of the arch 7 and discharges downwardly with the long dimension in cross-section of the sheet of fuel delivered thereby parallel to the front wall. The two outer burners are set at right angles to the middle nozzle.

The manner in which the arrangement is operated to secure substantially balanced flame conditions is diagrammatically indicated in Figs. 2, 3 and 4. At low ratings fuel would only be supplied thru the middle nozzle as shown in Fig. 2. At an intermediate rating the powdered coal would be supplied thru the outer burners and the middle burner would be cut out as indicated in Fig. 3. At

maximum rating all three burners would be supplying coal as indicated in Fig. 4.

It is customary to set the burners alike, that is they would all be disposed as is the central burner or they would all be disposed as are the outer burners of Fig. 1. If now, with either arrangement, a burner or burners are cut in or cut out to meet the operating conditions described, it will be seen that 10 it will be difficult to obtain a balanced flame condition. With the alternate arrangement of the burners a much more nearly uniform flame condition will result under all operating conditions.

15 In Fig. 5, I have illustrated an elaboration or development of the arrangement to take care of a larger furnace. It will be seen that the central burner may be used alone for very low ratings, or that the two burners on 20 either side of the central burner may alone be used; or that the middle and the two end burners may be used; with the production of substantially uniform or balanced flame conditions within the combustion chamber. 25 The inlets 9 are suitably controlled by dampers, so that these may be cut in and cut out as the occasion may demand.

The disposition of the burners alternately at right angles to one another, is one that 30 lends itself particularly well to the purposes of the invention. The independent control of the auxiliary air inlets also makes it possible to secure proper air admission for the various firing conditions described.

35 In Fig. 6 I have illustrated a modification which is applicable when it is desired to have a direct fired pulverized coal burning installation, i. e. one in which the burners are fed with fuel directly from the pulverizer. In 40 this case the burners are supplied by two mills, mill 15 supplying the fuel through pipe 17 and branch pipes 18 to the outside burners, and mill 16, which is preferably of smaller capacity, supplying the fuel to the middle 45 burner through 19.

In this construction mill 15 would be shut down at low ratings the fuel being supplied to the middle nozzle only by mill 16. At intermediate ratings mill 16 would be shut 50 down and the two end burners would be supplied by mill 15. At high ratings both mills and all burners would be used.

This arrangement could also be applied to the construction of Fig. 5, alternate burners 55 being supplied by the same mill, the larger mill supplying the outside and middle burners and the smaller mill supplying the other two.

I claim:

60 1. In combination, a combustion chamber and means for admitting sheets of finely divided fuel and air thereto comprising a row of independently controlled burners delivering substantially in the same direction and 65 having delivery ends elongated in cross-sec-

tion and alternately set substantially at right angles to each other.

2. In combination, a combustion chamber and means for admitting sheets of finely divided fuel and air thereto comprising a row 70 of independently controlled burners alternately set substantially at right angles to each other with the middle burner set to deliver a sheet substantially parallel with the front wall.

3. In combination, a combustion chamber and means for admitting sheets of finely divided fuel and air thereto comprising a row 75 of burners delivering substantially in the same direction and having delivery ends elongated in cross-section and alternately set approximately at right angles to each other.

4. In combination, a combustion chamber and means for admitting sheets of finely divided fuel and air thereto comprising a row 80 of burners having delivery ends elongated in cross-section and alternately set approximately at right angles to each other and delivering the fuel downwardly into the combustion chamber.

5. In combination, a combustion chamber and means for admitting sheets of finely divided fuel and air thereto comprising a row 85 of burners alternately set approximately at right angles to each other and delivering the fuel downwardly into the combustion chamber adjacent an upright wall thereof, together with means for admitting air at a plurality of points through such wall.

6. In combination, a combustion chamber, 90 a row of finely divided fuel burners delivering in one general direction and having flat nozzles set alternately cross-wise to each other, said burners having independent controlling means so that burners may be cut in or out, a plurality of air inlets adapted to supply combustion air up to maximum demands and positioned to deliver air adjacent the streams of fuel from the burners, and control means whereby inlets may be cut in or out as burners are cut in or out.

7. Apparatus for the burning of pulverized coal comprising a combustion chamber, and a plurality of fuel and air delivery burners directed thereto in the same general direction, said burners having delivery ends elongated in cross-section, the longer axes of the delivery ends of alternate burners being set cross-wise with relation to the longer axes of the delivery ends of the other burners.

8. Apparatus for the burning of pulverized coal comprising a combustion chamber, and a plurality of fuel and air delivery burners directed thereto in the same general direction, said burners having delivery ends elongated in cross-section, the longer axes of the delivery ends of alternate burners being set cross-wise with relation to the longer axes of the delivery ends of the other burners, together with independently operable fuel-de-

livery means to each set of alternate burners.

9. Apparatus for the burning of pulverized coal comprising a combustion chamber, and a plurality of fuel and air delivery burners directed thereinto in the same general direction, said burners having delivery ends elongated in cross-section, the longer axes of the delivery ends of alternate burners being set cross-wise with relation to the longer axes of the delivery ends of the other burners, together with independently operable fuel delivery means to each burner.

In testimony whereof, I have hereunto signed my name.
